DESIGN FOR A BABY WALKER

Frank P. Fletcher, Pasadena, Calif., assignor to
Fletcher Aviation Corp., Pasadena, Calif., a
corporation of California

Application April 9, 1945, Serial No. 118,909

Term of patent 14 years

(Cl. D14—14)

To all whom it may concern:

Be it known that I, Frank P. Fletcher, a citizen of the United States, residing in Pasadena, in the county of Los Angeles and State of California, have invented a new, original, and ornamental Design for a Baby Walker, of which the following is a specification, reference being had to the accompanying drawing, forming part thereof.

In the drawing,

Fig. 1 is a rear three-quarter perspective view of a baby walker, showing my new design;

Fig. 2 is a side elevational view;
Fig. 3 is a front elevational view;
Fig. 4 is a top plan view;
Fig. 5 is a rear elevational view; and
Fig. 6 is a bottom plan view thereof.

I claim:

The ornamental design for a baby walker, as shown.

FRANK P. FLETCHER.
